DESIGN FOR A DRESS

Hilda Jerome, Philadelphia, Pa., assignor to Rosenau Bros. Inc., Philadelphia, Pa., a corporation of Pennsylvania

Application June 8, 1938, Serial No. 77,679

Term of patent 3½ years

To all whom it may concern:

Be it known that I, Hilda Jerome, a citizen of the United States, residing at Philadelphia, in the county of Philadelphia and State of Pennsylvania, have invented a new, original, and ornamental Design for a Dress, of which the following is a specification, reference being had to the accompanying drawing, forming part thereof:

I claim:

The ornamental design for a dress, as shown.

HILDA JEROME.
